CLAIM

We claim the ornamental design for a display panel with an icon image, as shown and described.

DESCRIPTION

FIG. 1 is a view of a display panel with an icon image in an operating environment; and,

FIG. 2 is a front view of the display panel with an icon image of FIG. 1.

The broken line showing of a device in FIG. 1 and the broken line showing of a display screen with graphical user interface in FIG. 2 are included for the purpose of showing portions of the article which form no part of the claimed design.

1 Claim, 2 Drawing Sheets

FIG.1

FIG.2
